WINDOW AND OPERATING MEANS
THEREFOR

Harold Coleman, Chicago, Ill.

Application July 5, 1941, Serial No. 401,206

6 Claims. (Cl. 189—72)

My invention relates to windows and improved operating means by which a closure member may be moved into and out of closure position. It is one of the objects of the invention to provide an improved arrangement of parts by the use of which the leading edge of the closure member upon an opening operation is given first an oblique movement edgewise and outwardly away from the window frame so as to cut down to a minimum the frictional engagement of the movable closure member on the stationary frame parts. In the preferred construction, the closure member is provided with weather-strips along its side edges in position to engage suitable portions of the window frame assembly, the arrangement being such that the oblique movement of the closure member at the start of an opening operation carries the weather-strips out of position for operative engagement with the frame so that the closure member moves easily and smoothly and the wear on the weather-strips is kept to a minimum. In the arrangement as illustrated, weather-strips are provided both along the side edges of the closure member and along the side bars of the window frame, one of such sets of weather-strips being in channel or groove form so as to receive a rib or tongue portion of the cooperating strip therein for making a tight joint at each edge of the closure member. In this arrangement, the oblique movement of the closure member at the start of the opening operation is particularly helpful, since it assures the benefit of a highly effective joint when the window is closed while at the same time permitting the closure member to be moved easily out of closure position when desired.

It is one of the objects of this invention to provide a readily operable smooth working mechanism for attaining the desired ends as above set forth, whereby the desired oblique movement of the closure member in one direction at the start of an opening operation and the reverse oblique movement in the opposite direction at the end of the closure operation shall be effected automatically by the operation of the window handling mechanism.

It is another object of this invention to improve arrangements of this type in sundry details hereinafter pointed out. The preferred means by which the several objects have been attained are illustrated in the accompanying drawings and are hereinafter specifically described. That which I believe to be new and desire to cover by this application is set forth in the claims.

In the drawings,

Fig. 1 is a face view of a window embodying my improvements, with a considerable portion of the lower part of the structure broken away at an intermediate point.

Fig. 2 is substantially a vertical sectional view taken on the line 2—2 of Fig. 1.

Figs. 3 and 4 are views corresponding to portions of Fig. 2 but showing changed positions of certain of the parts.

Fig. 5 is substantially a horizontal sectional view taken on the line 5—5 of Fig. 1.

Fig. 6 is a view similar to Fig. 5 but showing a changed position of certain of the parts; and

Figs. 7 and 8 are substantially vertical sectional views taken at the line 7—7 and the line 8—8, respectively, of Fig. 1.

Referring now to the several figures of the drawings, in which corresponding parts are indicated by the same reference characters, 15 indicates a frame member in the form of a casting having a window opening therein, comprising a top frame bar 16, side bars 17 and 18, and a bottom frame bar 19. The drawings show a metal plate 20 extending downwardly from the bottom frame bar 19, the other bars being provided with suitable openings 21 for connection of wall plates therewith.

Just below the window opening, there is a heavy cross bar 22 extending across in horizontal position, comprising a housing portion 23 at an intermediate point therealong, such cross bar being rigidly connected at its ends with the frame member 15 in slightly spaced relation forwardly with respect to the frame member. The bar 22 and the housing 23 are provided with downwardly extending lugs 24 and 25, respectively, in which are mounted downwardly extending rods 26 connected at their lower ends by a bar 27. Between the rods 26, an operating screw 28 is mounted, rotatably mounted in a suitable bearing in the housing 23 at its upper end, and having an anti-friction bearing on the bar 27 at its lower end, as is best shown in Fig. 8. The arrangement is such that the rods 26 and the screw 28 are strongly braced with respect to each other.

For closing the window opening, a piece of plate glass 29 is employed, provided at its lower edge with a heavy cross bar 30 having a downward extension 31 at its middle portion, such extension 31 having a forwardly extending flange 32 at its lower edge. In the flange 32, there are two notches 33 in which collars 34 are adjustably mounted, such collars 34 being slidably

mounted on the rods 26. Just above the collars 34, other collars 35 are slidably mounted on the rods 26, coiled springs 36 being interposed between the collars for holding the collars 35 normally raised to the limit of their motion with respect to the collars 34. Links 37 are pivotally connected at their forward ends with the collars 35 and at their rear ends with the downward extension 31, the pivotal connection with said extension being effected by means comprising lugs 38. The arrangement is such that when the collars 35 are moved downwardly toward the collars 34 from the position shown in Fig. 4 to the position shown in Fig. 2, the downward extension 31 and the plate glass 29 connected therewith are moved backwardly toward the right in said figures.

As is best shown in Fig. 2, the lower edge of the plate glass 29 is provided with a rubber gasket 39 which is secured in position by screws 40 taking into a cross bar 41. The arrangement is such that when the plate glass is moved to the upward limit of its motion the gasket 39 has tight engagement with the frame bar 19 so as to seal the joint between the glass and the bar.

The means for moving the glass 29 upwardly, and downwardly with respect to the frame bar 15 comprises a spiral pinion 42 fixedly connected with the screw 28 and meshing with a spiral gear 43 fixedly connected with a spur pinion 44 which in turn meshes with a spur gear 45 driven by a crank handle 46 positioned at the front face of the housing 23. When the gear 45 is driven by means of the crank, the screw 28 is rotated, serving to move upwardly or downwardly a nut 47 having a threaded connection with the screw, the direction of movement of the nut depending of course upon the direction of rotation of the screw. The nut 47 has sliding engagement with a notch 48 in the flange 32 so as to cause the glass to move with the nut.

The arrangement is such that at about the end of the upward movement of the glass 29, the collars 35 are brought into contact with the lugs 24 and 25 so as to limit the upward movement of the front ends of the links 37, with the result that upon continued upward movement of the glass the links are swung upwardly toward their horizontal position, serving to move the glass backwardly toward the right in Fig. 2 for bringing the gasket 39 into sealing engagement with the bar 19 at the end of the upward movement of the glass. When the glass thereafter is moved downwardly again by a reverse rotation of the screw 28, the springs 36 insure that the links 37 shall be biased to the limit of their motion as soon as the pressure on the collars 35 is relieved so as to cause the downward extension 31 and the glass definitely to move forwardly for carrying the gasket 39 out of engagement with the bar 19.

The means for sealing the window at its upper edge comprises a strip of sponge rubber 49 held in position by a sheet metal member 50. At opposite sides of the window, the side bars 17 and 18 are provided with channel members 51 opening inwardly, with a grooved sealing member 52 mounted at one side of each of the channels in position for engagement with a cooperative sealing member 53 mounted on the glass in the form of a rib or tongue. In the arrangement shown, the grooved sealing member is formed largely of felt, while the ribbed member 53 is bent into form from sheet metal so as to grip the edge of the glass for presentation of the rib effectively

to the groove. In the construction illustrated, the upper end portion of the front flange portion 54 of each of the channel members 51 is obliquely disposed so as to cooperate with the links 37 for moving the glass backwardly toward the frame member 15 when the glass approaches the upper limit of its movement.

By the use of my improvements, I have provided a highly useful arrangement. When the window is closed, the opening is completely sealed so as to prevent the entrance of water, for example, when employed in connection with a boat. The weather strips are arranged so as to resist a high degree of pressure without danger of any water seeping through any of the joints about the closure member. When, however, the closure member is moved edgewise out of closure position, the closure member is given an initial movement facewise for carrying the weather-strips out of engagement with each other so as to permit easy movement of the closure member and so as to keep to a minimum the wear and tear on the weather-strips and the operating parts.

While I prefer to employ the form and arrangement of parts as shown by the drawings and as above described, my invention is not to be limited to such arrangement except so far as the claims may be so limited, it being understood that changes might well be made in the form and arrangement of the parts without departing from the spirit of the invention.

I claim:

1. In a window construction, the combination of a frame defining the window opening, a closure member, a guide with which said closure member has sliding engagement for directing said closure member into position opposite to said opening when moved to the limit of its motion in one direction, link means having a pivotal bearing on said closure member at their rear end portions and a sliding pivotal bearing on said guide at their front end portions, yielding means normally holding the forward end portions of said link means at a higher level than that of the rear end portions, and means adapted by engagement therewith to limit the movement of the forward end portions of said link means so as to give the link means a swinging movement while the closure member continues to advance at about the end of the movement of the closure member into closure position to press the closure member firmly against said frame for effecting a tight closure of said opening.

2. In a window construction, the combination of a frame defining the window opening, a closure member, a guide with which said closure member has sliding engagement for directing said closure member into position opposite to said opening when moved to the limit of its motion in one direction, link means having a pivotal bearing on said closure member and on said guide, spring means serving normally to hold said link means in oblique position with respect to said guide for holding said closure member in spaced relation to said frame, and means adapted at about the end of the movement of the closure member into closure position to engage said link means for causing them to swing against the action of said spring means toward perpendicular position with respect to said guide for pressing said closure member away from the guide and into tight closure relationship to said opening.

3. In a window construction, the combination of a frame defining the window opening, guides

arranged in spaced parallel relation to each other at one side of the opening and in perpendicular position with respect to the side edge of the opening, a closure member slidably mounted on said guides so as to be movable edgewise into and out of closure position with respect to said opening, bearing devices slidably mounted on said guides, links pivotally connected with said closure member and with said bearing devices, springs normally pressing said bearing devices into position for holding said links in oblique position, and means for moving said closure member into closure position with respect to said opening serving at the end portion of such closure movement to bring said bearing devices into engagement with a portion of said frame so as to cause said links on the continued movement of the closure member to move toward perpendicular position with respect to said guides for pressing the closure member tightly against said frame about said opening.

4. In a window construction, the combination of a frame defining a window opening and comprising a bar extending across in horizontal position adjacent to the lower edge of the opening, guide rods rigidly connected at their upper ends with said cross bar, a closure member slidably mounted on said rods so as to be movable edgewise into and out of closure position with respect to said opening, collars slidably mounted on said rods, links pivotally connected with said closure member and with said collars, coiled springs on said rods normally pressing said collars upwardly into position for holding said links in oblique position, and means for moving said closure member upwardly into closure position with respect to said opening serving at the end portion of said closure movement to bring said collars into engagement with said cross bar for limiting the upward movement of the collars so as to cause said links to move toward perpendicular position with respect to said guide rods for pressing the closure member tightly against the frame.

5. In a window construction, the combination of a frame defining the window opening, guide means comprising a rod fixedly mounted in vertical position below the window opening at about

the middle of the opening transversely thereof, a closure member slidably mounted at its lower edge portion on said rod so as to be movable edgewise into and out of closure position with respect to said window opening, means for moving said closure member along said rod, means comprising a link having a pivotal bearing on said closure member at its rear end portion and a movable pivotal bearing on said rod at its front end portion, yielding means normally holding the forward end portion of said link in raised position with respect to its rear end portion, and means for limiting the upward movement of the front end portion of the link so as to give the link a swinging movement for pressing the closure member backwardly against the frame for effectively closing said opening.

6. In a window construction, the combination of a frame defining the window opening, guide means comprising two rods fixedly mounted in vertical position and in slightly spaced relation to each other below the window opening at about the middle of the opening transversely thereof, a closure member slidably mounted at its lower edge portion on said rods so as to be movable edgewise into and out of closure position with respect to said window opening, a screw member rotatably mounted between said two rods with its lower end securely braced in position between said rods, a nut threaded on said screw member and operatively connected with said closure member so that upon rotary movement of the screw member said closure member is moved vertically, means for rotating said screw member, means comprising links having pivotal connection with said closure member at their rear end portions and sliding pivotal connection with said rods at their front end portions, yielding means normally holding said links biased upwardly at their front end portions, and means for limiting the upward movement of the front end portions of said links so as to give the links a swinging movement downwardly toward perpendicular position with respect to said guides for pressing the closure member backwardly against the frame for effectively closing said opening.

HAROLD COLEMAN.
